UNITED STATES PATENT OFFICE.

BIANCA PRINCE AND HENRIETTA PRINCE, OF NEW YORK, N. Y.

COMBINED BRASSIÈRE AND GIRDLE.

1,212,677.

Specification of Letters Patent. Patented Jan. 16, 1917.

Application filed December 9, 1915. Serial No. 65,885.

To all whom it may concern:

Be it known that we, BIANCA PRINCE and HENRIETTA PRINCE, citizens of the United States, residing at New York, in the county 5 of New York and State of New York, have invented new and useful Improvements in Combined Brassières and Girdles, of which the following is a specification.

This invention relates to a garment which 10 essentially includes a brassière for supporting the breast of a woman, and a girdle forming a permanent contiguous extension or fixture of the lower portion of the brassière, for drawing or looping across the hips 15 and over the thighs.

The object of the invention is to provide 20 a substitute for a corset, designed to permit entire freedom of motion, and it is so constructed as to preserve the appearance or contour of the figure.

The garment is particularly adapted for 25 all sports, and being tight fitting to the figure it will avoid harmful effects during the most strenuous or vigorous exercise.

The novel features of the invention are 30 more fully described in the following specification and claims and illustrated in the accompanying drawings in which:

Figure 1 represents a front elevation of 35 a garment embodying this invention. Fig. 2 is a rear view of the same. Fig. 3 is a fragmentary view showing the inner portion of the back. Fig. 4 is a vertical section taken along the line 6 6 of Fig. 3. Fig. 5 is a similar section taken along the line 7 7 of Fig. 3.

In the accompanying drawings is shown a 40 garment consisting of a brassière having a neck portion *a* a yoke *b* with armholes *c*, including front and rear body sections *d* and *d'* respectively extending to the waist of a figure. The yoke *b* is provided with strips *e* formed of elastic webbing to set over the shoulder-blades of a figure and permit free arm movement.

An opening *f* extends from the neck to 45 the lower front portion of the garment and the opening is preferably held closed by means of hook and eye fasteners. Each side 50 of the opening is constructed of a strip of material *g* having an integral lower extension *h*. The extended portion below the waist line of the brassière constitutes a girdle with front side sections *i* and back sections *j*. The front sections *i* are yieldingly joined to the extension *h* by means of

elastic webbed front members *k*. As indicated in Fig. 1 the upper portions of these members *k* are secured to the lower front part *d* of the brassière by stitching the web 50 to the fabric.

The central portion of the rear of the brassière consists of a plurality of strips of elastic webbing *m* which are secured to the fabric on each side of the rear by stitching 65 along the sides of the back section. The ends of the webbing are covered by a strip of binding *n* best seen in Fig. 3, to give a neat finish to the article. The lower rear portion *j* of the girdle has connected to it a 70 webbed elastic member *o* the edge portions of which as shown in Fig. 3 are secured to the sides of the girdle sections *j* by sewing, while the ends are covered by a tape binding 75 *p* stitched in the fabric.

The waist portion of the garment is provided with a webbed elastic band *q* embracing the back and extending partly about the front with its ends secured to the upper side portions of the webbed members *k*, 80 while a tape binding *r* as shown in Fig. 1, covers each end of the band. A series of vertically positioned webbed elastic straps *s* connect the front and back lower portions of the brassière with the girdle. These 85 straps have their upper and lower ends concealed or covered by the tape binding *t* as indicated in Fig. 3. The straps are superposed one being at the outside and the other at the inside, relative to the belt so as not 90 to interfere with the tensioning of the belt and at the same time form a strong durable structure.

The brassière and the girdle have darts 95 *u* cut in the fabric to gather and give the garment the correct shape to snugly fit the figure.

The front of the girdle is stiffened by a series of flexible whalebones *v* to hold in the stomach and retain the shape of the forward 100 lower portion of the garment. The front and rear portions of the girdle adjacent to the elastic strips of webbing also have whalebones *w* embedded in the fabric to give shape to the garment and coact with the figure. The lower ends of the front and rear part 105 of the girdle have suspended therefrom a number of garters *x* for holding stockings. It will be readily understood that the brassière will closely fit the body, thus holding 110 the fleshy masses over the shoulder-blades and keeping the busts in place. The

strips of elastic arranged along the back stretch when the lungs are expanded and hence do not retard breathing.

At the front the brassière and the girdle extension are of one piece so that they cannot shove out of place relative to each other. By having the whalebones located in the front sections the stomach of the figure when seated cannot protrude and 10 injury to the organs during heavy exertion is obviated.

The waist line is kept supple and yielding by means of the elastic band while the vertical superposed straps of elastic stretch 15 to take up any downward pull of the girdle in connection with the brassière. In this construction the ends of the band *q* are fastened to the upper portion of the elastic members *h*, the other parts of the band being 20 unattached; the band will freely expand circumferentially independent of the elastic vertical straps. In other words the vertical straps furnish a yielding connection between the girdle and brassière sections, with the band sliding between the 25 straps, each pair being made to loop the face and back of the band. The girdle fits closely about the hips reaching some distance below the waist and the elastic members 30 on each side of the front extension permit expansion of the chest without injuring the configuration or shape of the garment.

Another advantage of this device is that 35 it has no steels and thereby gives free and unimpeded movement of the body when exercising.

As indicated in the drawing the band *q* will compensate for the expansion and contraction 40 of the waist and abdomen, especially after any laborious exercise or exertion of the body. The elasticity of the band practically insures a snug fit at all times, also avoids gathering of fabric at 45 the waist line, and prevents wrinkling of the upper and lower sections of the garment.

It will be readily understood that the 50 series of vertical elastic straps *s* will permit unrestricted movement of the chest and limbs of the body. In other words when stooping or sitting down the straps will automatically adjust the girdle relative to the brassière. Each strap has 55 independent stretch or tension so that it will take up any movement of the chest, hip and thigh without impairing the graceful shape of the girdle and brassière.

Copies of this patent may be obtained for five cents each, by addressing the "Commissioner of Patents Washington, D. C."

We claim:

1. In a garment of the kind described, the 60 combination with a brassière, of a girdle extending from the lower portion of the brassière, and an elastic connection between the brassière and the girdle, said connection being elastic lengthwise of the garment. 65

2. In a garment of the kind described, the combination with a brassière having elastic members disposed in the back thereof, of a girdle extending from the lower portion of the brassière and adapted to girdle the hips, and an elastic connection between the girdle and the brassière. 70

3. In a garment of the kind described, the combination with a brassière, of a girdle extending from the lower portion of the 75 brassière, elastic connections between the brassière and the girdle, and elastic members arranged along the front and back of the girdle.

4. In a garment of the kind described, the 80 combination with a brassière, of a girdle extending from the lower portion of the brassière and adapted to loop the hips, elastic connections between the brassière and girdle, and elastic members along the back 85 of the brassière and the back and front of the girdle.

5. In a garment of the kind described, the combination with a brassière, of a girdle extending from the lower portion of the 90 brassière, elastic strips between the brassière and the girdle, and an elastic band free of said strips and adapted for circumferential expansion.

6. In a garment of the kind described, the 95 combination with a brassière, of a girdle extending from the lower portion of the brassière, yielding members disposed along the back of the brassière and front of the girdle, elastic strips connected to the lower 100 edge of the brassière and the upper edge of the girdle, and an elastic band between the brassière and the girdle but free of the edges thereof and free of the strips, said band being connected to the garment at its 105 ends only and being adapted for circumferential expansion.

In testimony whereof we have hereunto set our hands in the presence of two subscribing witnesses.

BIANCA PRINCE.
HENRIETTA PRINCE.
